(57) **CLAIM**

The ornamental design for a back panel, as shown and described.

DESCRIPTION

FIG. 1 is a front, top, right-side perspective view of a back panel;

FIG. 2 is a rear, top, left-side, perspective view thereof;

FIG. 3 is a front view thereof;

FIG. 4 is a rear view thereof;

FIG. 5 is a top view thereof;

FIG. 6 is bottom view thereof;

FIG. 7 is a right-side view thereof; and,

FIG. 8 is a left-side view thereof.

The broken lines in the drawings depict portions of the back panel that form no part of the claimed design.

1 Claim, 6 Drawing Sheets
